UNITED STATES PATENT OFFICE.

CHARLEY A. ZETTERSTRAND, OF HILLSBOROUGH, NORTH DAKOTA.

HEATING-DRUM.

SPECIFICATION forming part of Letters Patent No. 601,368, dated March 29, 1898.

Application filed October 9, 1896. Serial No. 608,405. (No model.)

To all whom it may concern:

Be it known that I, CHARLEY A. ZETTERSTRAND, a citizen of the United States, residing at Hillsborough, in the county of Traill and State of North Dakota, have invented a new and useful Heating-Drum, of which the following is a specification.

My invention relates to heating-drums; and its object is to provide an improved construction of the same which shall possess superior advantages with respect to efficiency in operation.

In the accompanying drawings, Figure 1 is a view in perspective of my improved heating-drum. Fig. 2 is a vertical central sectional view of the same.

In the said drawings the reference-numeral 1 designates a central pipe connected at top and bottom with approximately cylindrical-shaped heads 2. This pipe communicates with the lower of said heads. Inside of and parallel with said central pipe 1 are four pipes 3, which pass into said heads 2, said central tube 1 being closed at its upper end, the four inclined pipes 3 opening outside of the heads 2. Communicating with said heads 2 is a series of vertical pipes 4, which are concentric to the said pipe 1. The outer ends of said heads are formed with flues 5.

The operation is as follows: The lower of said heads is connected with the smoke-pipe of a stove or heater by means of the induction-flues. The products of combustion will enter the lower head and pass into the cen-

tral pipe 1. They will circulate in this pipe 35 and return to the said lower head and pass up through the vertical pipes 4 to the upper head 2, and from thence through the education-flue 5^a in said head to another smoke-pipe leading to a chimney or flue, the draft 40 being upward. During the circulation of the heated products of combustion through said pipes 4 said pipes will become heated and, through radiation, will heat the room in which the heater is located. At the same time air 45 will enter the pipes 3 at the bottom and, becoming heated, will escape through the pipes at the top.

I am aware that prior to my invention heating-drums have been made with vertical 50 pipes. I therefore do not claim such a combination, broadly; but

What I do claim as my invention, and desire to secure by Letters Patent, is—

A heating-drum comprising the two heads, 55 a central pipe communicating with the lower head and attached to the upper head, a series of smaller pipes within the central pipe and passing entirely through the heads, and a series of outer pipes 4, the opposite ends of 60 each of which enter the heads, in combination with the smoke-pipes 5 5, one attached centrally to each head, substantially as described.

CHARLEY A. ZETTERSTRAND.
